MOTHPROOFING COMPOSITION

Wallace Colman and Herbert L. J. Haller, Washington, D. C., assignors to Claude R. Wickard, as Secretary of Agriculture of the United States of America and to his successors in office

No Drawing. Application December 2, 1941,
Serial No. 421,333

11 Claims. (Cl. 167—37)

(Granted under the act of March 3, 1883, as
amended April 30, 1928; 370 O. G. 757)

This application is made under the act of March 3, 1883, as amended by the act of April 30, 1928, and the invention herein described and claimed, if patented, may be manufactured and used by or for the Government of the United States of America for governmental purposes without the payment to us of any royalty thereon.

This invention relates to mothproofing of fibers and fabrics made therefrom.

The principal object of our invention is to render fabrics, and like materials, resistant to attack by fabric pests, such as, for example, clothes moths, carpet beetles, and the like.

Another object of our invention is to fix the chemical agent or agents in the fabrics so that they are not readily removed by washing or other cleansing means.

According to our invention, fabrics and the like have applied to them, preferably by spraying or immersion, a composition whose principal ingredient is isonitrosoacetanilide which has been dissolved in acetone. This compound may be used alone, but we prefer to apply it with certain other compounds which act to fix the mothproofing ingredient in the fiber or fabric. We prefer to use benzoic acid, phthalic acid, salicylic acid, benzamide, p-toluene sulfonyl chloride, and p-toluene sulfonyl-N-butylamide, but we do not limit ourselves to these materials. Other carboxylic acids, sulfonic acids, their acid chlorides and amides, or mixtures thereof, may also be employed.

Our invention may be practiced as illustrated below:

Example 1.—Immerse woolen cloth in a 0.5% solution of isonitrosoacetanilide in acetone for a period of about ten minutes, and then allow the cloth to dry. In this way, the cloth is rendered resistant to the attack of clothes moths, carpet beetles, and the like.

Example 2.—Immerse woolen cloth in a 0.5% solution of isonitrosoacetanilide and phthalic acid in substantially equal proportions, by weight, in acetone for a period of about ten minutes, and then allow the cloth to dry. In this way, the cloth is rendered resistant to the attack of clothes moths, carpet beetles, and the like; and

the chemical agents become fixed therein, and are not readily removed.

Example 3.—Immerse woolen cloth in a 0.5% solution of isonitrosoacetanilide and benzoic acid in substantially equal proportions, by weight, in acetone for a period of about ten minutes, and then allow the cloth to dry. In this way, the cloth is rendered resistant to the attack of clothes moths, carpet beetles, and the like; and the chemical agents become fixed therein, and are not readily removed.

Example 4.—Immerse woolen cloth in a 0.5% solution of isonitrosoacetanilide and salicylic acid in substantially equal proportions, by weight, in acetone for a period of about ten minutes, and then allow the cloth to dry. In this way, the cloth is rendered resistant to the attack of clothes moths, carpet beetles, and the like; and the chemical agents become fixed therein, and are not readily removed.

Example 5.—Immerse woolen cloth in a 0.5% solution of isonitrosoacetanilide and benzamide in substantially equal proportions, by weight, in acetone for a period of about ten minutes, and then allow the cloth to dry. In this way, the cloth is rendered resistant to the attack of clothes moths, carpet beetles, and the like; and the chemical agents become fixed therein, and are not readily removed.

Example 6.—Immerse woolen cloth in a 0.5% solution of isonitrosoacetanilide and p-toluene sulfonyl-N-butyl amide in substantially equal proportions, by weight, in acetone for a period of about ten minutes, and then allow the cloth to dry. In this way, the cloth is rendered resistant to the attack of clothes moths, carpet beetles, and the like; and the chemical agents become fixed therein, and are not readily removed.

Example 7.—Immerse woolen cloth in a 0.5% solution of isonitrosoacetanilide and p-toluene sulfonyl chloride in substantially equal proportions, by weight, in acetone for a period of about ten minutes, and then allow the cloth to dry. In this way, the cloth is rendered resistant to the attack of clothes moths, carpet beetles, and the like; and the chemical agents become fixed therein, and are not readily removed.

The following data sets forth the value of our invention:

COMPARISON OF RESISTANCE TO INSECT ATTACK OF
WOOLEN CLOTH, GIVEN A STANDARD MOTHPROOF-
ING TREATMENT, WITH THE SAME CLOTH
TREATED WITH ISONITROSOACETANILIDE

Table I

Isonitroso-acetanilide	Sodium silicofluoride	Check (no treatment)					
		#1	#2	#3	#4	#5

p-Toluene sulfonyl-N-butyl amide.....	97.3 76.2	28.0 48.8	10 6 6 10	61.4 63.2 33.1
Sodium silicofluoride.....	7.0	2		
Check.....	46.1 17.0	32.4 60.4	10 5 5 8	5 8 7 10

Each determination (unless otherwise noted) is the result of a test with ten partially grown larvae of *Anthrenus vorax*, Waterhouse, one of the most destructive species of fabric insects known. The samples of cloth were exposed to attack, under conditions favorable to the insect, for a period of six weeks. At the end of this time, the weight of the cloth destroyed and the number of larvae remaining alive were determined. All compounds were dissolved in acetone, with the exception of sodium silicofluoride, which was dissolved in water. All solutions were applied at a uniform strength of 0.5%, and, where two compounds were combined, they were used in approximately equal quantity by weight.

Other carboxylic acids, sulfonic acids, their acid chlorides and amides, or mixtures thereof, may be used with isonitrosoacetanilide. It is to be understood that the concentrations of the various compounds and their proportions in the solvent may be varied over a wide range, and other solvents may be substituted for the acetone mentioned in the above examples.

Having thus described our invention, what we claim for Letters Patent is:

1. A moth-proofing agent comprising isonitrosoacetanilide.
2. A moth-proofing agent comprising isonitrosoacetanilide and an acid chosen from the group consisting of carboxylic acid and sulfonic acid.
3. A moth-proofing agent comprising isonitrosoacetanilide and an acid chloride of carboxylic acid.
4. A moth-proofing agent comprising isonitrosoacetanilide and an acid chloride of sulfonic acid.
5. A moth-proofing agent comprising isonitrosoacetanilide and an amide of carboxylic acid.
6. A moth-proofing agent comprising isonitrosoacetanilide and an amide of sulfonic acid.
7. A moth-proofing agent comprising isonitrosoacetanilide and phthalic acid.
8. A moth-proofing agent comprising isonitrosoacetanilide and salicylic acid.
9. A moth-proofing agent comprising isonitrosoacetanilide and benzamide.
10. A moth-proofing agent comprising isonitrosoacetanilide and p-tolene sulfonyl-N-butyl amide.
11. A moth-proofing agent comprising isonitrosoacetanilide and p-tolene sulfonyl chloride.

WALLACE COLMAN,
HERBERT L. J. HALLER.
